UNITED STATES PATENT OFFICE

FRANK MASTRANGELO AND ALPHONSO MASTRANGELO, OF FITCHBURG, MASSACHUSETTS, ASSIGNORS TO ANGEL NOVELTY COMPANY, OF FITCHBURG, MASSACHUSETTS, A CORPORATION OF MASSACHUSETTS

DESIGN FOR A CHAIR OR SIMILAR ARTICLE OF FURNITURE

Application filed March 22, 1932. Serial No. 43,264. Term of patent 14 years.

To all whom it may concern:

Be it known that we, FRANK MASTRANGELO and ALPHONSO MASTRANGELO, both citizens of the United States, both residing at Fitchburg, in the county of Worcester and State of Massachusetts, have invented a new, original, and ornamental Design for a Chair or Similar Article of Furniture, of which the following is a specification, reference being had to the accompanying drawing, forming part thereof.

The figure is a perspective view showing our new design applied to the back of a chair, with the rest of the chair in dotted lines. It can be applied to table ends and other furniture.

We claim:

The ornamental design for a chair or similar article of furniture as shown.

FRANK MASTRANGELO.
ALPHONSO MASTRANGELO.
